(57) **CLAIM**

The ornamental design for an inverter, as shown and described.

DESCRIPTION

FIG. 1. is a front perspective view of the front, right, and top sides of an inverter showing our new design;

FIG. 2. is a front view thereof;

FIG. 3. is a rear view thereof;

FIG. 4. is a top plan view thereof;

FIG. 5. is a bottom plan view thereof;

FIG. 6. is a right side view thereof; and,

FIG. 7. is a left side view thereof.

FIG. 8. is an enlarged perspective view of a part 8-8 shown in FIG. 1;

FIG. 9. is an enlarged front view of a part 9-9 shown in FIG. 2; and,

FIG. 10. is an enlarged cross-sectional view of a cut part 10 at a part 10-10 shown in FIG. 6.

The broken lines shown represent portions of the inverter and form no part of the claimed design.

The dash-dot broken lines represent boundaries of the enlarged parts and form no part of the claimed design.

1 Claim, 10 Drawing Sheets
